Des. 179,863
Patented Mar. 12, 1957

179,863

RACK FOR MAGAZINES OR OTHER ARTICLES

Sigel G. Roush, Newark, Ohio

Application May 3, 1956, Serial No. 41,336

Term of patent 14 years

(Cl. D33—10)

The view of the drawing is a perspective of a rack for magazines or other articles, showing my new design.

The characteristic features of my design are shown by means of full lines in the drawing.

I claim:

The ornamental design for a rack for magazines or other articles as shown and described.
